UNITED STATES PATENT OFFICE

119,714

DESIGN FOR AN AIRPLANE

Hall L. Hibbard, North Hollywood, and Clarence L. Johnson, Burbank, Calif., assignors to Lockheed Aircraft Corporation, a corporation of California

Application June 27, 1939, Serial No. 85,724

Term of patent 14 years

To all whom it may concern:

Be it known that we, Hall L. Hibbard and Clarence L. Johnson, citizens of the United States, residing at North Hollywood and Burbank, respectively, in the county of Los Angeles and State of California, have invented a new, original, and ornamental Design for an Airplane, of which the following is a specification, reference being had to the accompanying drawings, forming a part thereof:

Fig. 1 of the drawings is a perspective view of an airplane embodying the new design as it would appear from a point off to the side and slightly forward and above the airplane while the latter would be in flight with its main and nose landing wheels retracted;

Fig. 2 is a side elevation of the airplane;
Fig. 3 is a perspective view of the airplane as it would appear from a point off to the side and slightly forward and below the airplane while the latter would be in flight with its main and nose landing wheels retracted.

Fig. 4 is a front elevation of the subject airplane.

We claim:

The ornamental design for an airplane, substantially as shown.
